(57) **CLAIM**

The ornamental design for a child potty seat, as shown and described in FIGS. 1-9, and the ornamental design for a child potty seat, as shown and described in FIGS. 10-18.

DESCRIPTION

FIG. 1 is a top perspective view of a child potty seat according our new design;

FIG. 2 is a front bottom perspective view of the child potty seat shown in FIG. 1;

FIG. 3 is a rear top perspective view of the child potty seat shown in FIG. 1;

FIG. 4 is a front elevation view of the child potty seat shown in FIG. 1;

FIG. 5 is a rear elevation view of the child potty seat shown in FIG. 1;

FIG. 6 is a left side elevation view of the child potty seat shown in FIG. 1;

FIG. 7 is a right side elevation view of the child potty seat shown in FIG. 1;

FIG. 8 is a top plan view of the child potty seat shown in FIG. 1; and,

FIG. 9 is a bottom plan view of the child potty seat shown in FIG. 1.

The broken lines in the drawings, which illustrate environmental structure or boundaries of the embodiments of the exemplary child potty seat, do not form a part of the claimed design.
